UNITED STATES PATENT OFFICE.

JAMES M. WELCH, OF LAKE PORT, CALIFORNIA.

POLE ANCHOR.

Application filed December 17, 1921. Serial No. 523,157.

To all whom it may concern:

Be it known that I, JAMES M. WELCH, a citizen of the United States, residing at Lake Port, in the county of Lake and State 5 of California, have invented a new and useful Pole Anchor, of which the following is a specification.

This invention relates to post supports, the primary object of the invention being to 10 provide means embracing the lower end of a post for securing the post against lateral movement.

Another object of the invention is to provide a metallic support, which will withstand 15 weather conditions insuring against the post rotting at its base.

A still further object of the invention is to provide a support which may be driven into the ground surface, thereby eliminating 20 the necessity of forming a hole in the ground surface to receive the securing device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawings:—

Figure 1 is an elevational view of a support disclosing one end of the post as set 35 cured thereto.

Figure 2 is a vertical sectional view through the support and lower end of the post positioned therein.

Figure 3 is a sectional view taken on line 40 3—3 of Figure 1.

Figure 4 is a fragmental rear elevational view of the upper portion of the support, and lower extremity of a post.

Referring to the drawings in detail, the 45 reference character 5 designates the lower portion of the support which is tubular in formation and provided with a tapering member 6 adapted to be driven into the ground surface on which a post is to be supported.

Positioned within the lower portion 5 is a hollow liner 7 which is provided with a head 8 that is bored to accommodate the spike 9, that is of a length to extend beyond 50 the end of the tapered portion 6, as shown by Figure 1 of the drawings, so that the

spike will embed itself in the ground surface.

As shown, the liner 7 extends upwardly terminating at a point above the lower tubular portion 5, where the same receives the tubular extension 10 which is carried by the disk 11 and which depends therefrom. The disk 11 is formed with suitable openings to accommodate bolts 12 which pass through 60 registering openings in the disk 11 and base 13, which base is formed preferably of wood, and is of a diameter greater than the diameter of the disk 11.

The bolts 12 are of lengths to extend 70 through openings in the right angled flanges 14 of the sectional collar 15, which collar has inwardly extending flanges 16 tapered to embed themselves in the base of the post which is indicated at 17. The sections of 75 the collar may move with respect to each other, and to this end the sections are provided with right angled ears 18 which are apertured to accommodate the bolts 19 for permitting the sections to be adjusted with 80 respect to each other, to adapt the same for use in connection with posts of various diameters.

Chains indicated at 20 are secured to one of the sections as clearly shown by Figure 85 3 of the drawings, the opposite sections being formed with hook members 21 to accommodate one of the links of the respective chains. Thus it will be seen that by properly adjusting the chains 20, and operating 90 the nuts 22 of the bolts 19, the sections of the collar may be brought into close engagement with the post associated therewith.

In order that moisture will be excluded 95 from the liner 7, a packing 23 is provided, which seals the connection between the liner 7, lower section 5 and tubular extension 10.

In the use of the device, the lower member 5 is first driven into the ground surface, and the tubular liner 7 is positioned therein. 100 The spike 9 is now passed through the opening in the head 8 by inserting a suitable bar through the liner 7. The extension 10 is now positioned over the upper end of the liner 7 and the disk 11 bolted to the base 105 13. It follows that the sectional collar is positioned on the base 13 ready to receive the post, after which the sections are clamped into close engagement with the post.

From the foregoing it will be seen that 110 I have provided novel means for supporting the post, the structure of the support being

such as to eliminate the necessity of forming an opening in the ground surface to position the same, it being only necessary to drive the elements of the support into the ground surface.

What is claimed as new is:

1. A post support including a lower tubular portion having a tapered extremity adapted to be driven into the ground surface, a hollow liner normally positioned within the lower portion and having its upper end extending above the upper end of the lower portion, a disk having a tubular extension normally positioned over the upper end of the liner, a base positioned on the disk and a sectional collar secured to the base, and said sectional collar adapted to embrace the lower extremity of a post.

2. A post support embodying a lower portion, a hollow liner positioned within the lower portion, a head at one end of the hollow liner and having an opening, a spike movably positioned within the opening and adapted to extend therethrough, a disk having an extension normally positioned over the liner, a sectional collar adapted to em-

brace the lower extremity of a post, a base positioned between the collar and disk, and means for securing the collar, base and disk together.

3. A post support embodying a lower portion having a tapered extremity adapted to be positioned in the ground, a tubular liner within the lower portion, means extending through the tubular liner and adapted to be driven into the ground for securing the lower portion against movement, a disk having a tubular extension normally positioned over the liner, a base bolted to the disk, a sectional collar on said base normally positioned centrally of the lower portion and adapted to be clamped around the base of the post, inwardly extending flanges forming a part of the collar, said flanges adapted to embed themselves in the post.

In testimony that I claim the foregoing as my own, I have hereto affixed my signature in the presence of two witnesses.

JAMES M. WELCH.
